UNITED STATES PATENT OFFICE.

ELMER U. AMES, OF PHILADELPHIA, PENNSYLVANIA, ASSIGNOR TO H. BRINTON COMPANY, OF PHILADELPHIA, PENNSYLVANIA, A CORPORATION OF PENNSYLVANIA.

NEEDLE-CONTROLLING MECHANISM.

1,149,884.

Specification of Letters Patent. Patented Aug. 10, 1915.

Application filed October 15, 1914. Serial No. 866,821.

To all whom it may concern:

Be it known that I, ELMER U. AMES, a citizen of the United States, residing in Philadelphia, Pennsylvania, have invented 5 certain Improvements in Needle-Controlling Mechanism, of which the following is a specification.

My invention consists of certain improvements in the construction of needle-actuating cams for knitting machines, and more particularly for "circular" machines in which the needle cylinders, or in some instances the knitting cams, receive a reciprocating movement such, for example, as is required in forming the toe or heel of a 15 stocking.

One object of the invention is to provide a knitting machine with mechanism which will retain the needles in their proper course 20 during the knitting operation and thereby avoid injury to said machine.

Another object of said invention is to so construct a "fine gage" knitting machine including the above mentioned mechanism, 25 that the needles while under the stitch cams will be kept under control and will thereby be prevented from losing their stitches.

These objects and other advantageous ends I attain as hereinafter set forth, reference being had to the accompanying drawings in which,

Figure 1 is a sectional plan of part of a knitting machine equipped with my invention; Fig. 2 is a development of certain 35 elements of a knitting mechanism including my invention; Fig. 3 is a view similar to Fig. 2 showing certain of the parts in other positions; Fig. 4 is a perspective view of my invention; Fig. 5 is a fragmentary end 40 elevation of the mechanism shown in Fig. 4; and Fig. 6 is a section taken on the line a—a, Fig. 4.

In the above drawings, I have shown a needle cylinder 1 grooved at 2 for the reception of the needles and so mounted as to be capable of reciprocation as indicated by the double headed arrow Fig. 1. A ring 3 partially surrounds the cylinder 1 and frictionally engages the same so as to be moved 45 with it. The desired friction between the ring and cylinder may be obtained either by making the inside diameter of the ring smaller than the outside diameter of the

cylinder and then "springing" said ring on the latter or it may be caused by some 55 means external to the ring.

The ends 4 and 5 of the ring 3 are inclined away from each other and the space between them provides room for the stitch cams 6 and 7, an upper center cam 8 and a 60 lower center cam 9 which constitute the principal knitting cams of the machine. In addition the lower portions of the ends of the ring 3 are recessed at 10 and 11 for the reception of two cams 12 and 13 respectively, each of which has a beveled edge 14 fitting under the correspondingly overhung beveled edge 15 of said ring 3. The cams 12 and 13 are each provided with a lateral 65 projection 16 having a slot 17 for the reception of a screw 18 whereby it may be adjustably secured to a supporting structure 19 (Fig. 1). By having the projections 16 integral with or rigidly fixed to the cams 12 and 13, the cam faces 20 and 21 may be 70 adjusted relatively to the cam faces 6^a and 7^a of the stitch cams 6 and 7, so as to provide passages α and α' of the proper width to allow the needle butts to pass there-through. The object of this construction is 75 to maintain the width of these passages constant even though the ring 3 may be moved into and out of contact with the upper portions of said stitch cams 6 and 7 as is necessary for example during the reciprocating 80 movement of the needle cylinder, it having been noted that if the needles are not kept under the control of the stitch cams for a short time before and after passing under the lowest portions of the latter they are 85 apt to vibrate and thereby lose their stitches. In "fine gage" machines, even more than in coarse gage machines, the needles if not kept under control as just described, are apt to lose their stitches because in the former 90 the hooked ends of the needles being small will, upon the slightest vibration or jar, shake off the loops of yarn which they are 95 carrying.

It is obvious that with my invention, by 100 having the stitch cams 6 and 7 fixed with respect to the cams 12 and 13, it is practically impossible for the needles, after having been lowered by the stitch cams, to move out of their prescribed course, since the passages 105 α and α' are only of sufficient width to allow

the needle butts to pass therethrough. Under operating conditions, if it be assumed that the cams 6, 7, 8 and 9 are stationary and that the cams 12 and 13 are fixed with respect to the cams 6 and 7, movement of the cylinder 1 in one direction will move the ring 3 until its cam face 5 moves away from the stitch cam 7 sufficiently to provide an outlet passage z for the needles after they have passed under the stitch cam 7. The cam surface 4 is also brought into contact with the stitch cam 6 (see Fig. 2) thus closing the passage previously existing between it and said cam. During the movement of the needle cylinder in the opposite direction (see Fig. 3) the ring 3 is so moved that its cam face 5 is brought into contact with the stitch cam 7 to close the passage z above mentioned while the cam face 4 is moved away from the stitch cam 6 to provide an outlet passage z' for the butts of the needles after they have passed under the stitch cam 6 (see Fig. 3). It will be noted that by having the faces 14 of the cams 12 and 13 beveled (see Figs. 4 to 6) and the faces 15 of the ring 3 correspondingly overhung, the needle butts cannot possibly jam between said cams 12 and 13 and the ring but will ride smoothly over the joints between these parts because the butt of each needle as it passes upwardly will have one portion in contact with the cam face of the ring 3 before another portion thereof has left the cam 12 or 13.

35 I claim:—

1. The combination in a knitting machine of stitch cams; cams respectively adjacent said stitch cams and having faces coöperating therewith to form needle passages; and 40 a ring having portions extending over said second mentioned cams and movable into and out of contact with the stitch cams to

alternately provide and close passages adjacent the same.

2. The combination in a knitting machine 45 of stitch cams; cams mounted adjacent the lower portions of said stitch cams and co-operating therewith to form needle passages; and a ring having its ends movable into and out of contact with the stitch cams 50 to alternately provide and close passages adjacent the same, the ends of the ring being formed to slide over the second mentioned cams.

3. The combination in a knitting machine 55 of stitch cams; lifting cams mounted adjacent the lower portions of the stitch cams and coöperable therewith to form needle passages; and a ring having its ends movable into and out of contact with the stitch 60 cams to alternately provide and close needle passages adjacent the same, the ends of said ring being recessed to receive said lifting cams, the adjacent edges of said parts being 65 beveled in the same direction to provide a continuous support for the needle butts.

4. The combination in a knitting machine of stitch cams; cams respectively adjacent said stitch cams and having faces coöperating therewith to form needle passages; and a member having portions the full width of the needle passages coöperating with said second mentioned cams and movable into and out of contact with the stitch cams, to 70 alternately provide and close needle passages.

In testimony whereof, I have signed my name to this specification, in the presence of two subscribing witnesses.

ELMER U. AMES.
